United States Patent Office.

REUEL ROBINSON, OF SAN FRANCISCO, CALIFORNIA.

Letters Patent No. 70,121, dated October 22, 1867.

IMPROVED LIFE-PRESERVER.

The Schedule referred to in these Letters Patent and making part of the same.

TO ALL WHOM IT MAY CONCERN:

Be it known that I, REUEL ROBINSON, of San Francisco, county of San Francisco, State of California, have invented a Berth Life-Boat and Armor combined; and I do hereby declare the following description and accompanying drawings are sufficient to enable any person skilled in the art or science to which it most nearly appertains to make and use my said invention without further invention or experiment.

The object of my invention is to provide a life-preserved or boat for vessels, so constructed that it will not occupy the space required for freight or other purposes, and furnish to each person a simple and complete life-boat and armor combined, in which one having provisions can live at sea for an indefinite time, and be a safe and ready means of escape from the ship in case of wreck.

To do this I construct a raft or float so that it will fit the bottom of the berth, made of thin boards or other material, and of sufficient depth to give it the required buoyancy and strength, say six (6) feet long by two (2) feet wide, and four (4) inches deep, more or less, with water-tight compartments. Through the centre of this I make an opening, about four (4) feet long, sharp at each end, and twenty (20) inches wide at the middle, and place in it an armor to fit it, made of rubber or other water-proof material, about twenty inches deep, with a narrow strip or piece of wood or other material for the bottom. This armor is secured to the sides of the opening. Below the float, and on either side of the narrow bottom, are the legs. Above the top of the float is the upper portion of the armor, made large enough to fit the person, and is drawn in closely about the neck by means of a cord. Large sleeves are confined about the wrists by elastic wristbands, so that the hands can be drawn inside when desired. In front, through the cover or armor, is an opening, which, when not in use, may be closed with a string or other device to render it water-tight. A small vessel is placed inside, so that the person can attend to the calls of nature, and bail out the water in case of leakage. When used for the berth-bottom the armor is folded into the opening, making an even surface, and secured by a piece of light duck, laced tightly around. This duck may be set for a sail in light winds, or a signal for passing ships, a small mast being furnished for the purpose, to be placed in front of the person in the armor. Paddles are lashed to each side of the craft, which can be used, one in each hand, by loosely fastening the ends of the handles to the mast, in front. Inside there is a strap to fit over the shoulder, to facilitate the adjustment of the armor and support the whole weight while on deck. A person can lower himself by making fast to a strap just in front of the armor. When in the water he will sit across and rest upon the narrow, stiff bottom of the lower armor, which is large enough to allow the occupant free movement or change of position, and space for a small quantity of water and provisions. Nearly the whole weight of the person being below the main bearings, it cannot capsize.

To more fully illustrate and describe my invention, reference is had to the accompanying drawings and letters marked thereon, of which—

Figure 1 is a side view.

Figure 2 is a side sectional elevation.

Figure 3 is a plan.

A represents an oblong float, with sharp, flat ends, constructed of boards, with side and end pieces, leaving spaces between the upper and lower surfaces. This float should be made as near water-tight as possible. An opening, B, is made through the float, having two acute and two obtuse angles large enough to admit the body, through which is placed an India-rubber armor, C, which is attached to the sides of the opening in a permanent manner, just below the arms, the whole being large enough to admit the body and give free movement to the limbs. Below the body of the armor, and between it and the upper portion of the legs, I place a stiff piece of board or other material, D, for a seat, whose sides are shaped so as to conform to the contour of the legs. This seat is placed lengthwise with the armor, and affords a sufficient space in front to store a small quantity of provisions and water. A small ladle, E, is also placed inside of the armor, and attached to it by a string, by which the passenger may attend to the calls of nature, as well as bail out the water which may enter in case of leakage. This is done, the hands and arms being free, by means of an opening, F, made in front of the armor, which is kept tightly closed by a small cord when not used for the above-described purpose.

In order to steer and propel the craft, a light pair of oars, $\alpha\alpha$, are provided, and when not in use may be lashed to the sides of the float; and a small, light mast, with sails and halyards all ready to set, is clewed up at one side of the craft, and in case of need this mast is set in front of the armor, in a depression made for the purpose in the deck of the craft

I claim the frame A, provided with air-tight compartments, and a flexible case for the legs, body, and arms, and having a seat, D, and opening, F, all substantially as described.

In witness whereof I have hereunto set my hand and seal.

REUEL ROBINSON. [L. S.]
